(57) CLAIM

The ornamental design for a miniature golf hole, as shown and described.

DESCRIPTION

FIG. 1 is a front perspective view of a miniature golf hole showing our new design;

FIG. 2 is a top front perspective view thereof;

FIG. 3 is a top rear perspective view thereof;

FIG. 4 is a front view thereof;

FIG. 5 is a rear view thereof;

FIG. 6 is a side elevational view thereof;

FIG. 7 is an opposite side elevational view thereof; and,

FIG. 8 is a top plan view thereof.

The broken lines in the figures show portions of the miniature golf hole that form no part of the claimed design.

1 Claim, 8 Drawing Sheets
